CLAIM

The ornamental design for a media streaming accessory, as shown and described.

DESCRIPTION

FIG. 1 is a perspective view of a portion of a media streaming accessory according to an embodiment of our design;

FIG. 2 is a top elevation view thereof;

FIG. 3 is a bottom elevation view thereof;

FIG. 4 is a right side elevation view thereof;

FIG. 5 is a left side elevation view thereof;

FIG. 6 is a rear elevation view thereof;

FIG. 7 is a front elevation view thereof;

FIG. 8 is a perspective view of a portion of a media streaming accessory according to another embodiment of our design;

FIG. 9 is a top elevation view thereof;

FIG. 10 is a bottom elevation view thereof;

FIG. 11 is a right side elevation view thereof;

FIG. 12 is a left side elevation view thereof;

FIG. 13 is a rear elevation view thereof; and,

FIG. 14 is a front elevation view thereof.

Broken lines are environmental only and form no part of the claimed design.
